UNITED STATES PATENT OFFICE.

WILLIAM A. WHITMORE, OF GALVA, ILLINOIS; RALPH D. WHITMORE EXECUTOR OF
SAID WILLIAM A. WHITMORE, DECEASED.

SPOUT FOR CONVEYING MATERIALS.

1,288,335.

Specification of Letters Patent. Patented Dec. 17, 1918.

Application filed November 4, 1916. Serial No. 129,469.

To all whom it may concern:

Be it known that I, WILLIAM A. WHITMORE, citizen of the United States, residing at Galva, in the county of Henry and State of Illinois, have invented certain new and useful Improvements in Spouts for Conveying Materials; and I do hereby declare that the following is a full, clear, and exact description of the invention, which will enable others skilled in the art to which it appertains to make and use the same.

This invention relates to improvements in spouts. It relates more particularly to improvements in spouts or conduits for handling various materials such as grain, ore, coal, sand, and the like.

The invention relates also to improvements in a spout or conduit of that type made up of a series of parts or sections wherein one terminates within the other, forming an adjustable spout used in loading cars, vessels and the like.

The object of the invention is to provide a construction in a spout or conduit section wherein the bottom portion that becomes worn by the passage of materials thereover may be renewed without the necessity of renewing the entire section.

The invention also pertains to certain details of construction as will be pointed out herein and form the subject of some of the claims.

To the end that the invention may be understood, I have provided the accompanying drawing, in which,

Figure 1 is a side elevation of a spout or conduit consisting of a number of sections loosely related through suitable connections.

Fig. 2 shows, in perspective, one of the sections.

Fig. 3 is a transverse section of the same on line α — α , Fig. 2.

Fig. 4 shows also, in perspective, one of the sections with its removable bottom detached; and,

Fig. 5 shows the removable bottom, in perspective.

Grain spouts to which my invention has particular reference are usually made up of a series of sections conical in form the small end of one extending into the large end of the other, the sections being attached to one another by chains or other types of loose connections, so that the parts form a flexible conduit, in use describing a curve or arc.

As the grain passes through the jointed conduit each section is subjected to a continuous wear at substantially one spot upon its bottom which is rapidly worn through. Holes thus created mean loss of grain and the sections when thus affected are then turned over and the opposite side used until rendered unfit for use by wearing action whereupon they must be discarded and new ones provided.

My invention contemplates furnishing for each section a removable bottom section to take this wear which can be provided at a small cost compared with the expense attached to the provision of new sections and those bottoms can be provided as often as required. The sections themselves are never required to be taken down or replaced, lasting indefinitely. Furthermore, said sections may be constructed each with an opening in its wall which is covered by the described hollow section. Thereby the sections may be constructed at much lower cost than when using complete metal sheets that would make a solid section as will appear herein.

A A indicate several pipe sections each of which is preferably conically formed whereby its pointed end or nose may enter the end of an adjacent section as clearly shown in Fig. 1, all the sections being suitably connected through flexible members, such as chains B, and allowed to move relatively in a lateral direction as well as in a longitudinal direction. This, however, is common practice and I lay no claim thereto of itself.

Each section consists in this instance of the frustum of a hollow cone though it is to be understood that other forms may be used. It is provided with an opening C in one side leaving end portions D and E.

F is a somewhat tapered shell portion which enters and fits snugly the part A, its ends being supported upon the described portions D E, see Fig. 2, the longitudinal edges extending well beyond the side margins of the said opening C whereby the latter is entirely closed, as in Fig. 2.

G is a guide secured to each outer side of the portion F at its small end, being so disposed thereon that when the said portion is introduced into the section it will be guided to its proper position and prevented turning axially.

Said guides include at each outer end the

outwardly bent free end H which engages over the outer surfaces of the portion D as clearly shown in Figs. 1 and 2. When thus seated in position the portion F is held in place by friction, its small end overlying said portion D to protect it being worn by the material handled.

The relation of the sections as shown in Fig. 1 is such that the portions F may be readily withdrawn or placed in position without trouble and the change may be made in a very few minutes. That is to say, the space between the small end of one section and the large end of the next readily permits the insertion for withdrawal of the part F. When the sections are conical in form the inserted portion or bottom F will close snugly the opening C without danger of the conveyed material passing through it. For that reason the conical form of section is the preferred one although, as stated, other shapes may be used.

My invention also contemplates inserting into a tubular section having no opening in its side, a portion such as F which would protect the metal of said section, although from the standpoint of cheapness in the saving of material a section having an opening is, perhaps, preferable.

30 The sections, if each has an opening therein, may be made up of parts, if desired, so that a full sheet of metal need not be required in its manufacture.

A conduit made up of a series of connected sections, making it flexible, is necessarily subjected to more wear than a rigid conduit since each section is straight and each is disposed at an angle to its neighbor. Its surface that receives the grain from a section higher up, therefore, is subjected to greater wear at one point as the material strikes it at an angle to the plane of the receiving surface, whereas in a straight conduit the material merely moves along its entire surface wearing the said entire surface. Therefore, a conduit of movable telescoping sections, each section having a removable bottom, is a very important change new in the art.

50 Slight changes may be made in the construction of the section and its renewable bottom portion without departing from the spirit of the invention and the meaning of the appended claims.

55 Having thus described my invention, I claim:

1. An article of manufacture comprising

a sheet metal spout section in the form of a frustum of a hollow cone having an opening through the lower portion of its wall terminating short of the ends of such sections leaving terminal bands completing the circumference of the section at such points, a removable bottom plate shaped to conform to the interior of such section and insertible therein through its larger end and when in position in such section covering said opening and overlying the longitudinal wall margins thereof and said end band portions, and means to prevent axial turning and longitudinal shifting of said bottom plate in the spout section, substantially as described.

2. In combination with a tubular grain spout section having an opening extending around it for substantially one half its circumference extending to near each end of the section, said section including a connecting portion at each end to complete its tubular form at each its ends, and an insertible portion adapted for insertion into the section to and overlie the opening and overlap those portions of the sections lying at each side of the opening and to overlie the said connecting portions.

3. As an article of manufacture a tubular spout section having an opening in one of its walls, and a single rigid removable section lying upon the inner walls of said sections covering said opening and overlying those parts of the said portion at the side of said opening, and extending substantially to the extremity of the section at its discharge end, and securing means extending from the portion through the opening and engaging the outer surface of the section.

4. An article of manufacture, comprising a spout section consisting of a frustum of a hollow cone having an opening in its wall extending throughout substantially one half the circumference thereof and terminating near each end of said section, and a single removable portion lying within the said section overlying the opening and the margins surrounding the opening and conforming to the contour of the said wall having said opening.

In testimony whereof I affix my signature, in presence of two witnesses.

WILLIAM A. WHITMORE,
